UNITED STATES PATENT OFFICE

91,697

DESIGN FOR AN ICE-CREAM SCOOP

Ralph C. Bailie, Milwaukee, Wis.

Application December 27, 1932, Serial No. 46,626

Term of patent 3½ years

To all whom it may concern:

Be it known that I, RALPH C. BAILIE, a citizen of the United States, residing at Milwaukee, in the county of Milwaukee and State of Wisconsin, have invented a new, original, and ornamental Design for Ice-Cream Scoops, of which the following is a specification, reference being had to the accompanying drawing, forming part thereof.

I claim:

The ornamental design for an ice-cream scoop, as shown.

In testimony whereof I affix my signature at 6083 Plankinton Building, Milwaukee, Wisconsin.

RALPH C. BAILIE.
